UNITED STATES PATENT OFFICE.

GUSTAV STICKLEY, OF MORRIS PLAINS, NEW JERSEY.

DESIGN FOR A REMOVABLE FRONT FOR FIREPLACES.

42,789.

Specification for Design.

Patented July 9, 1912.

Application filed April 29, 1911. Serial No. 624,268. Term of patent 14 years.

To all whom it may concern:

Be it known that I, GUSTAV STICKLEY, a citizen of the United States, residing at Morris Plains, in the county of Morris, State of New Jersey, have invented and produced a new, original, and ornamental Design for Removable Fronts for Fireplaces, of which the following is a specification, reference being had to the accompanying drawings, forming a part thereof, in which the design consists in the form and ornamentation of the face of the front.

The design comprises the front —a— di-

vided into rectangular figures by means of parallel bars —b— intersecting horizontal bars —c— at substantially right angles, and the back ground of the rectangular figures having a mottled effect as shown at —d—.

What I claim is:

The ornamental design for a front for fire places as shown and described.

GUSTAV STICKLEY.
